SPEEDOMETER

Charles Stoecklin, Paris, France, assignor to
Societe Anonyme Tel, Paris, France

Application January 9, 1929, Serial No. 331,366

5 Claims. (Cl. 235—104)

This invention relates to speedometers of the known periodic-counter type which include in their construction a drive shaft, an oscillatively mounted pinion which may be carried by a rocking lever adapted to be driven by the said drive shaft, two gear trains symmetrically disposed with respect to the said pinion, a central indicating shaft common to the gear trains and adapted to control the movements of an indicating pointer or other equivalent part, a horological movement for driving cam or equivalent means to periodically produce engagement and disengagement of the pinion alternately with the two gear trains and for stopping and releasing the said gear trains.

With such devices as hitherto constructed, the horological movement drives a shaft carrying one cam for causing engagement and disengagement of the pinion with the gear trains, and another cam for operating mechanism to cause the stopping and releasing of the said gear trains.

According to the present invention, in speedometers of the type to which the invention relates, a single cam element, which may be in the form of an eccentric or otherwise, is provided for producing engagement and disengagement of the pinion alternately with the two gear trains and also for stopping and releasing the said gear trains.

Apparatus constructed according to the invention differs from apparatus of the known type consequently in that its mechanism is considerably simplified. Moreover, it permits of the use of robust elements for given overall dimensions and cheapens the cost of manufacture and upkeep.

My invention will be more readily understood by those skilled in the art with reference to the accompanying drawings forming part of this specification and in which—

Fig. 1 is a front view of my device with the front dial-carrying plate removed;

Fig. 2 is a sectional view taken on a line passing through the axes A, B, and C;

Fig. 3 is another sectional view as seen from below and taken substantially on the horizontal line passing through the axis D;

Figs. 4 and 5 are detail views of a modified form of mechanism;

Fig. 6 is a sectional view through another modified form of mechanism; and

Fig. 7 is a detail of a stop device thereof.

Referring to the drawings more in detail, a shaft 1, controlled directly or indirectly by the vehicle or other member whose speed is to be

measured, transmits its movement through the medium of a pinion 2 rigid with shaft 1 to a toothed wheel 3. A pinion 4 is mounted on the same shaft 36 with the toothed wheel 3, and is adapted to rock from left to right in a manner well known in the art under the action of an arm 27, for periodically driving the wheels 5 or 22, the arm 27 being controlled, for example, through the medium of an eccentric 28, adapted to become displaced in a slot 38 (Fig. 1). The eccentric 28 turns about the shaft D by any suitable means and in particular may be tributary to a horological movement shown diagrammatically in Fig. 3 and including a friction barrel 33, an escapement wheel 35 and a balance wheel 34. The said eccentric acts directly on the arm 27 and consequently on the pinion 4 as well as on pawls 29 and 30 respectively subjected to the action of springs 31 and 32.

It will be noted that this well-known oscillating movement imparted by the arm 27 moves the shaft 36 to the right or to the left upon which shaft are mounted the wheels 3 and 4.

The indicating gear train shown on the left hand side of Fig. 2 comprises a wheel 22 adapted to be driven from the pinion 4, through the required angular distance and against the action of a spring 23. The wheel 22 carries a pin 18 on its surface, which is adapted to contact with a stop pin 79 fixed to the framework, to limit the return movement due to the action of the spring. Coaxial with but free to turn independently of the wheel 22, is a toothed wheel 15 having a projecting pin 17, with which the projection 18 of the wheel 22 is adapted to co-act. 16 is a return spring normally for keeping the pin 17 pressed into contact with the projection 18, the spring 16 being fixed on the one hand to the arbor of the wheel 15 and on the other hand to the framework. When the wheel 22 is driven by the pinion 4, consequently the projection 18 carries round with it the pin 17 and consequently turns the wheel 15 against the action of its return spring 16. The pawl 30 co-operates under the action of the eccentric 28 with the wheel 15.

The indicating gear train on the right hand side of Fig. 2 comprises parts corresponding exactly with those on the left hand side. In this right hand train the wheel 5 which is adapted to be driven from the pinion 4 has a controlling return spring 6, and a projection 20 from the surface thereof adapted to come against a stop 21 fixed to the framework. 7 is the wheel coaxial with the wheel 5 but free to turn independently thereof, the wheel 7 having a pin 19 with which the

projection 20 co-acts, and a return spring 40. The pawl 29 controlled by the eccentric 28 co-
operates with the wheel 7.

10 is a spindle carried in suitable bearings in
5 the framework and having the indicator hand 39
fixed thereto. This spindle 10 has fixed thereto
so as to turn therewith a projection or arm 11,
and the spindle has mounted to freely turn there-
on two wheels 8 and 14. The wheel 15 of the left
10 hand gear train meshes with the wheel 14 and the
wheel 7 of the right hand gear train meshes with
the wheel 8. 9 is a spring attached to the frame-
work on the one hand and on the other hand to
the spindle 10, the action of the spring tending
15 always to return the hand 39 to zero.

12 is a pin projecting from the wheel 8 and
coming in the path of the arm or catch 11, and
13 is a corresponding pin projecting from the
wheel 14 and also coming into the path of the
20 arm or catch 11.

With the above construction, it follows that
by the action of the eccentric 28 the pinion 4
for a precise period of time drives the wheel 5,
during which time the setting of the parts is such
25 that the pawl 30 holds the wheel 15 from return
movement under the action of its spring 16,
whilst the pawl 29 is freed from the wheel 7,
allowing it to be turned by the action of the pro-
jection 20 on the pin 19, and then also by the
30 action of the eccentric 28, for another precisely
similar period of time, the pinion 4 is freed from
the wheel 5 and brought into engagement with
the wheel 22 and simultaneously the pawl 29
caused to hold the wheel 7 from movement whilst
35 the pawl 30 frees the wheel 15, this action con-
tinuing, so that by the timed movements of the
eccentric 28 the pinion 4 is alternately engaged
with the wheel 5 and the wheel 22.

When the pinion 4 is in driving engagement
40 with the wheel 5, it causes the projection 20 to be
moved from the stop 21 and the spring 6 to be
additionally stressed. The projection 20 engages
the pin 19 and turns the wheel 7 (the pawl 29
being free). The turning of the wheel 7 addi-
45 tionally stresses the spring 40. The wheel 7 turns
the wheel 8 and causes its pin or projection 12
to carry round with it the catch or arm 11, thus
turning the spindle 10 and additionally stressing
the spring 9. The spindle 10 carries round with
50 it the indicating pointer 39. When the pinion 4
leaves the wheel 5 and comes into engagement
with the wheel 22, the following actions take
place, those of the gear train on the right hand
side of Fig. 2 being first considered.

55 Immediately the wheel 5 is freed from the pin-
ion 4, it is then only under the control of the
spring 6, and by the stress of this spring, it is
turned back until its projection 20 contacts with
the stop 21, bringing the wheel 5 to rest. By this
60 action the projection 20 has left the pin 19, but
as the wheel 7 is now held by the pawl 29, this
wheel cannot turn backwards under the action of
the spring 40. Consequent upon this, the wheel
8 cannot turn back but its pin 12 continues to hold
65 the projection or catch 11 against the returning
stress of the spring 9 on the spindle 10, and thus
the indicator 39 remains in the set position.

By the pinion 4 meshing with the wheel 22, and
70 simultaneously the pawl 29 being engaged with
the wheel 7 and the pawl 30 freed from the wheel
15, the wheel 22 is driven so that it imparts ad-
ditional stress to the spring 23. Simultaneously
the projection 18 carries round with it the pin 17
of the wheel 15 and turns this wheel 15, impart-
75 ing additional stress to its return spring 16. The

turning of the wheel 15 turns the wheel 14 so
that its pin 13 moves towards the new position
of the catch or projection 11. If during this
second period, the speed of the shaft 1 has in-
creased, then the amount by which the wheel 22
is turned will be greater than the amount by
which the wheel 5 had previously been turned,
and consequently the pin 13 will move through
a greater angular distance than that previously
moved through by the pin 12. It will then contact
10 with the arm or projection 11 and carry this arm
or projection round through a greater angular
distance, and correspondingly turn the spindle
10 and increase the stress of the spring 9 and also
increase the reading of the pointer 39.

If on the other hand the shaft 1 turns to a less
extent during this second period than the first
period, then the pin 13 will not attain the arm or
projection 11, whilst should the speed of the shaft
1 remain constant, the pin 13 will just reach the
20 arm or projection 11.

When the pinion 4 is freed of the wheel 22 and
brought into engagement with the wheel 5, the
pawl 30 is brought into engagement with the
wheel 15 and the pawl 29 freed of the wheel 7.

The immediate consequences of this action are
that the wheel 22 now being only controlled by
the spring 23 is turned so that its projection 18
is brought back to the stop 79 and as now the
wheel 7 is freed from the pawl 29, it is only con-
trolled by its spring 40, and consequently turns
so that its pin 19 moves towards the projection
20 of the wheel 5, which projection 20 is moving
towards the pin 19 by the new drive imparted
thereto.

By the return movement of the wheel 7,
through the meshing of this wheel with the wheel
8, the pin 12 has been removed from its previ-
ously set position, and if in this position it was
holding the catch or projection 11 in position
(that is if the other pin 13 had not moved
through the same or a greater angular extent
than the pin 12) then by the movement of the
pin 12 from the catch or projection 11, the said
catch or projection 11 is freed, and the spindle
10 can be turned back by the return spring 9,
10 until the catch or projection 11 comes against
the pin 13, which limits the return movement.

In this manner the position of the spindle 10,
and consequently of the needle carried thereby,
50 indicates the speed.

The relative positions of the detents 29 and
30, the wheels 4, 7 and 15, and the eccentric 28,
are to a certain extent shown diagrammatically
in Fig. 1, and it should be realized that before
the pinion 4 comes out of mesh with either of
the wheels 7 or 15, the corresponding detent 29
or 30 comes into engagement with the said wheel
to prevent it running back under the action of
its controlling spring, and similarly, the detent
60 is removed from the wheel 7 or 15, as the case
may be, immediately after the said wheel has
been engaged by the pinion 4.

It should also be pointed out that equivalent
parts in modified forms to be described operate
65 in a similar manner.

Referring to Fig. 4, which shows another modi-
fication the control of the measuring pinion 4
mounted on the extremity of arbor 36 and driv-
ing alternately and periodically the wheels 5 and
22 is effected by means of a bell crank lever 41,
the extremity of one of the arms thereof carrying
the said pinion 4 loosely mounted thereon.
The said bell crank lever turns about a pivot 42
and the other arm which is shaped in a way to

form a spring along the part 44 thereof is provided with a ratchet 43 bearing on a cam 45 driven by a time movement. Said cam 45 carries on its periphery three projections 46 and 5 three notches 47 against which the ratchet 43 is drawn by a spring 48, the whole being arranged in a way that in accordance with the periphery of cam 43 the pinion 4 is actuated through three oscillations per revolution, that is, three engagements 10 for meshing with the wheel 5 and three other engagements for meshing with the wheel 22.

The stopping and liberation of wheels 7 and 15 is effected by a double leaf spring 50 rigid with lever 41 (Figs. 4 and 5) or on arm 27 (Fig. 1) but movable with them.

The springy part 44 of the bell crank lever 41 has for a purpose to prevent the production of faulty meshing of pinion 4 with the toothed 20 wheels 5 and 22. In fact if the bell crank lever 41 were rigid there could take place an error in the measurement of the instrument in the case where the teeth would strike each other instead of penetrating each other. The spring allows 25 slight flexing which permits driving of the gears as soon as the teeth come into engagement.

In order to overcome the above indicated inconvenience, I may in certain cases mount the shaft 36 as shown in Fig. 5, that is, in a throat 30 which serves as a bearing for pinion 4 upon which bears a leaf spring 49 allowing slight play of the shaft 36, which play serves the purpose of facilitating meshing of toothed wheels 5 and 22.

35 On the other hand the part 44 of the lever 41 could thus act directly on the heel of pawls 29 and 30 (Fig. 1) instead of carrying the flat spring 50 shown in Fig. 4.

The oscillation of the pinion 4 directly from 40 one wheel to another in a way that it is consecutively and alternatively in engagement with the wheel 5 and the wheel 22, has the following characteristics:

First.—Each of said engagements, that is, in 45 each direction and symmetrically, is accompanied by the four actions simultaneously, above noted, and all in the same measuring time of the device, and identical for each of these four actions, to wit, engagement, disengagement, stopping and liberation.

Therefore each engagement simultaneously establishes and breaks the meshing of the two groups of wheels.

Second.—Only a single time distributing member 55 in the form of a single cam (Fig. 4), an eccentric (Fig. 1) or the equivalent thereof is necessitated.

Third.—It is possible to specially dispose the direction lever of pinion 4 in a way that it can 60 yield when the teeth of said pinion 4 meet those of the wheels 5 or 22 or normally mesh with such teeth.

Figure 6 illustrates another embodiment of my device. The variable speed to be measured is 65 transmitted, for example, to the main shaft 74 and to what may be termed the pinion element, equivalent to the pinion 4 and constituted in this case by a two-face clutch member 61 loosely keyed thereon, the transmission being effected 70 by means of pinions 56 and 57. On the other hand, the shaft 52 which carries the cam 51 has imparted thereto, when the apparatus is in motion, a constant movement regulated by a horological movement, in a way that during the first 75 measuring time, the lever 58 which is pivoted

on the shaft 59 causes lateral engagement of the double wheel 61 with the wheel 62 which drives the ratchet wheel 65 by means of the pin 66.

The wheel 65 drives the member 63 by means of a lug 64. The member 63 transmits its displacement, proportional to the speed, to the pointer 71 by means of idlers 69 and 70. The wheels 62, 62', 65 and 65' are loosely mounted on the main shaft 74. Simultaneously with these operations, the stop lug 73 of the spring type 10 liberates the ratchet wheel 65, and the lug 73' stops the ratchet wheel 65' in the position where it happens to be and the double wheel 61 liberates the wheel 62'. The return spring 53 is adapted to constantly cause the end of lever 58 to 15 bear against a cam 51 carried by a shaft 52. Springs 68 and 68' return the wheels 65 and 65' to their initial positions. The springs 67 and 67' return the wheels 62 and 62' to their initial position and finally the spring 75 tends to return 20 the pointer 71 and the member 63 to the zero position when not retained by the lugs 64 and 64' of the wheels 65 and 65'.

Fig. 7 illustrates another method of stopping the wheel 65^a representing wheels 65 and 65' of 25 Fig. 6. In this case a spring arm 72^a is provided which carries at each extremity a pinion 73^a of which the teeth are adapted to be engaged at the desired moment with the teeth of the corresponding wheel 65 or 65', this pinion being 30 mounted on a spindle in such a way that it can rotate slightly so that the teeth thereof can come into engagement with the teeth of the wheel 65 or 65' even if the teeth in the two wheels to be engaged come opposite one another in the first 35 place. The pinion 73^a being only adapted for a limited amount of rotational movement on its supporting spindle serves, after engagement with the teeth of the wheels 65 and 65', to stop the rotation of such wheels.

While I have described what I deem to be the preferable forms of my device I do not wish to be limited thereto as there might be changes made in the forms of construction and disposition of parts without departing from the invention as comprehended within the scope of the appended claims.

Having described my invention what I claim as new and desire to secure by Letters Patent is:

1. A speedometer of the type described comprising in combination a drive shaft, a pinion element formed as a double toothed wheel and loosely keyed to said drive shaft, a pair of toothed wheels with which the said double toothed wheel is adapted to co-operate, a ratchet wheel associated with each of said pair of toothed wheels, an indicating gear train, means for driving said indicating gear train from the movements of the ratchet wheel, a single cam element, a horological movement for driving said single cam element, a lever element, one of the arms of which engages with the double toothed pinion element and the other of which is in operative engagement with the single cam element to impart an oscillating movement to the lever, thereby engaging the said pinion element periodically and alternately with the two co-operating toothed wheels, a double leaf spring carried by and moving with the said lever element, and detents carried at the ends of said double leaf spring for engagement with and disengagement from the said two ratchet wheels.

2. A speedometer of the type described comprising in combination a drive shaft, a pinion element formed as a double toothed wheel and

loosely keyed to said drive shaft, a pair of toothed wheels with which the said double toothed wheel is adapted to co-operate, a ratchet wheel associated with each of said pair of toothed wheels, an indicating gear train, lugs on each of said ratchet wheels, a stirrup member adapted to be engaged by said lugs and transmitting its movement to the indicating gear train, a single cam element, a horological movement for driving said single cam element, a lever element, one of the arms of which engages with the double toothed pinion element and the other of which is in operative engagement with the single cam element to impart an oscillating movement to the lever, thereby engaging the said pinion element periodically and alternately with the two co-operating toothed wheels, a double leaf spring carried by and moving with the said lever element, and detents carried at the ends of said double leaf spring for engagement with and disengagement from the said two ratchet wheels.

3. A speedometer of the type described comprising in combination a drive shaft, a pinion element formed as a double toothed wheel and loosely keyed to said drive shaft, a pair of toothed wheels with which the said double toothed wheel is adapted to co-operate, a ratchet wheel associated with each of said pair of toothed wheels, a pin on each of said pair of toothed wheels for engaging with a co-operating abutment provided on each of the said ratchet wheels, an indicating gear train, lugs on each of said ratchet wheels, a stirrup member adapted to be engaged by said lugs and transmitting its movement to the indicating gear train, a single cam element, a horological movement for driving said single cam element, a lever element, one of the arms of which engages with the double toothed pinion element and the other of which is in operative engagement with the single cam element to impart an oscillating movement to the lever, thereby engaging the said pinion element periodically and alternately with the two co-operating toothed wheels, a double leaf spring carried by and moving with the said lever element, and detents carried at the ends of said double leaf spring for engagement with and disengagement from the said two ratchet wheels.

4. A speedometer of the type described comprising in combination a drive shaft, a pinion element formed as a double toothed wheel and loosely keyed to said drive shaft, a pair of toothed wheels with which the said double toothed wheel is adapted to co-operate, a ratchet wheel associated with each of said pair of toothed

wheels, a pin on each of said pair of toothed wheels for engaging with a co-operating abutment provided on each of the said ratchet wheels, an indicating gear train, lugs on each of said ratchet wheels, a stirrup member adapted to be engaged by said lugs and transmitting its movement to the indicating gear train, a single cam element, a horological movement for driving said single cam element, a lever element, one of the arms of which engages with the double toothed pinion element and the other of which is in operative engagement with the single cam element to impart an oscillating movement to the lever, thereby engaging the said pinion element periodically and alternately with the two co-operating toothed wheels, a double leaf spring carried by and moving with the said lever element, and a friction pinion carried at each end of said double leaf spring for engaging with and disengaging from the said two ratchet wheels.

5. A speedometer of the type described comprising in combination a drive shaft, a pinion element formed as a double toothed wheel and loosely keyed to said drive shaft, a pair of toothed wheels with which the said double toothed wheel is adapted to co-operate, a ratchet wheel associated with each of said pair of toothed wheels, a pin on each of said pair of toothed wheels for engaging with a co-operating abutment provided on each of the said ratchet wheels, an indicating gear train, lugs on each of said ratchet wheels, a stirrup member adapted to be engaged by said lugs and transmitting its movement to the indicating gear train, a single cam element, a horological movement for driving said single cam element, a lever element, one of the arms of which engages with the double toothed pinion element and the other of which is in operative engagement with the single cam element to impart an oscillating movement to the lever, thereby engaging the said pinion element periodically and alternately with the two co-operating toothed wheels, a double leaf spring carried by and moving with the said lever element, and detents carried at the ends of said double leaf spring for engagement with and disengagement from the said two ratchet wheels, spring means for returning the said pair of toothed wheels to their initial position, further spring means for returning the ratchet wheels to their initial position, further spring means for returning the indicating gear train to its initial position and spring means for maintaining the end of the lever element in constant engagement with the single cam element.

CHARLES STOECKLIN.
